UNITED STATES PATENT OFFICE.

ALBERT B. CLISSON, OF SYRACUSE, NEW YORK, ASSIGNOR, BY MESNE ASSIGNMENTS,
TO THE PROSPERITY COMPANY, INC., A CORPORATION OF NEW YORK.

IRONING PRESS.

Application filed February 29, 1924. Serial No. 695,897.

This invention relates to ironing presses of the type having wide opening press jaws into and between which the work is arranged by the operator; and a primary object of the 5 invention is to provide such an ironing press as will guard and shield an operator's hands from coming into contact with the hot pressing surface of the machine.

Ironing presses of the type possessing substantially large area wide opening jaws or ironing members for ironing a large portion of the goods at one time are provided with a large polished metal surface which is hot and which is exposed to the operator when 10 the press opens and unless the operator exercises due care it often follows that his hands come in contact with the hot pressing surface with painful results.

It is fitting, therefore, that an object of my 20 invention is to provide instrumentalities for improving the ironing press in this regard in order that the operator may work more rapidly and not be handicapped by the close proximity of the hot exposed pressing surface; and I carry my purposes into effect by 25 providing, in one form of my invention, a guard or shield which automatically covers the hot pressing surface when the jaws open and automatically uncovers the pressing jaw 30 as the press closes. My improved ironing press therefore embodies a covered pressing surface when the press is open and an uncovered exposed hot pressing surface when the machine is closed.

35 The accompanying drawings illustrate an exemplary form of the invention the parts of which may be varied in construction and the mode of operation of which may be altered in some respects without departing 40 from the principle of the invention.

Figure 1 illustrates a side view of an ironing press with the jaws open and having the protective covering means drawn across the hot face of the ironing head; and Figure 45 2 shows a similar side view except that the press is closed and the guard thereof is removed from between the jaws to permit the ironing surface to engage the work.

Figure 3 shows a front fragmentary elevation of the machine with the jaws closed and a guard curtain rolled up out of the way; and Figure 4 illustrates a fragmentary plan view of the machine.

Figure 5 illustrates a fragmentary detailed view of the guard which in the pres-

ent invention is constructed in the form of a roller shield curtain.

Referring now more particularly to the drawings for a detailed description of the invention, there is shown a pressing machine 60 or an ironing press frame 10 provided with a press lever 11 pivoted on the frame at 12 and carrying an ironing head 13 on one end thereof while a short toggle link 14 is pivoted on the rear thereof. A lower longer 65 toggle link 15 is pivotally connected with the short link 14 and said toggle link 15 is preferably made integral with a pedal 16 which is pivoted on the frame at 17. A kick-off pedal 18' is pivoted on the frame at 19 and 70 is intended to thrust the pedal 16 upwardly to break the toggle 14-15 rearwardly to open the press and lift the ironing head 13 to the wide open position shown in Figure 1. Steam pipes 18 are employed for the purpose 75 of supplying steam to the head for heating it and it is to be noted that an ironing press of this character has its head 13 provided with a hot exposed polished metal surface for application against the goods spread 80 out upon the buck 20.

It is necessary for the head 13 to move away from the buck 20 for a substantial distance to provide a large opening into which the operator may thrust the goods and carry the work back over the buck 20 and it often happens that the operator, in rapidly spreading the goods upon the buck, burns his hands upon the hot pressing member 13 which must necessarily be exposed and not 90 covered by cloth in order that a dry gloss domestic finish be imparted to the goods during pressing operation. The main operating toggle 14-15 is so designed and constructed that the pedal 16 works through a limited 95 movement in order that it remains substantially close to the floor for a wide opening jaw movement.

The foregoing description covers in general one preferred type of ironing press which 100 I employ in producing the improvements constituting my invention and a description of my new combination will now be given.

In one form of my improved ironing press, a roller 25 is carried in brackets 26 105 along one longitudinal edge of the substantially long ironing head 13. The roller 25 carries a curtain 27 rolled thereupon and one edge of the curtain may be secured to a rod 28 the ends of which are guided in 110

2
a slot 29 formed in each bracket 26. The brackets 26 may be secured to any convenient part of one of the pressing jaws and is preferably secured to the ironing member which carries the exposed polished metal ironing surface. The brackets 26, while they may be attached to the press lever 11 are in this instance, for the purpose of illustration, secured to each end of the ironing head 13 as by the cap screws 30 though in actual practise other securing means may be used.

The brackets 26 are arranged parallel at each end of the ironing head and the rod 28 is adapted to move back and forth in the slots 29 for the purpose of drawing the curtain 27 across the hot pressing surface during the opening motion of the head. The roller 25 may have its shaft ends 31 fixed in the brackets 26 thereby permitting the roller 25 to be journaled upon the cylindrical shaft part 32. A coil spring 33 has one end thereof fixed to the roller and the other end thereof fixed to the shaft 32; and the spring acts to automatically wind up the curtain as the ironing head closes. This construction provides at all times either a tightly drawn curtain 27 stretching across the face of the head or tautly wound upon the roller. Other operating means may be employed to roll up the curtain.

Each end of the rod 28 is attached to a pull link 36, and the rear end of the link 35 is pivotally connected to the lower end of a swing link 37. The upper end of each swing link is journaled upon a transverse shaft 38 supported by a stationary frame 39. The frame 39 may be constructed in the form of a casting bolted on to the press frame 10 or may constitute an integral extension of the said frame 10.

An actuating arm 41 has its lower end anchored to the press lever hub 42 or to some other operating part of the ironing machine, and as the press lever 11 oscillates about its fulcrum joint 12, it follows that the said member 41 swings back and forth with its upper end slidably confined within a slot 43 made in each swing link 37. As the pedal 16 is forced downwardly, the actuating arm 41 moves forward with the press lever, the result of which is to pass the pull links 36 forwardly, thereby permitting the coil spring 33 to take in the curtain 27 and wind it upon the roller 25.

The operation of the machine is carried out automatically inasmuch as the said curtain, or shield of any other form, is connected to some moving part of the mechanism of the machine whereby the back and forth travel of the shield is automatically performed.

While I have described a roller curtain shield for the protection of the operator's

hands, it is to be noted that my application contemplates the use of shields or protectors of other types, and while for the purpose of clearness in description I have shown the actuating mechanism superimposed on the press, it is to be understood that the said actuating mechanism may preferably be altered and re-positioned in certain respects for the purpose of producing a compact simple design. 75

The invention is presented to fulfil the need felt for an ironing press protecting means capable of preserving the operator from harmful effects of the hot ironing head and which enables the operator to perform his work with dispatch. 80

What I claim is:

1. An ironing press comprising, cooperating ironing and pressing jaws, a heat guard, and operating means to move the guard into 85 position between the jaws of the press.

2. An ironing press comprising in combination, cooperating ironing and pressing jaw members into which the work is placed, means for opening and closing the press, 90 a guard and means for moving the guard across the face of one of the press jaws as the press opens to protect the operator's hands from one of the hot jaws while arranging the work in the press. 95

3. An ironing press comprising in combination, heated pressing members which open and close on the work and one of which has a heated and polished metal ironing and pressing surface, a movable guard 100 carried by the press, means which moves said guard across the heated and polished pressing surface when the press opens, to shield the operator's hands against the heat, and means to move said guard away from 105 the pressing surface as the press closes to permit the heated and polished surface to engage the work.

4. An ironing press comprising in combination, heated pressing members which open and close on the work and one of which has a heated and polished metal ironing and pressing surface, means for opening and closing the press, a heat shield, and mechanism operated by the press opening 110 and closing means for actuating the shield and driving it into the press as it opens and moving it out of the press as it closes. 115

5. An ironing press comprising in combination, heated pressing members which open and close on the work, one of the members having a polished and heated metal ironing and pressing surface, a guard member carried by the press and arranged to roll up when not in use and unroll when in use, and mechanism carried on press 120 employed to roll up the guard as the press starts its ironing operation to expose the hot ironing surface to the work and which unrolls to cover up the hot ironing surface 125 130

when the machine has completed the ironing operation.

6. An ironing machine comprising in combination, ironing jaws adapted to open and close on the work, pedal means arranged to travel through a relatively short distance, a connection established between the pedal and ironing jaws to execute a wide opening movement of the jaws to afford large opening for manually arranging the work in the machine, a heated pressing and ironing surface carried by one of the ironing jaws, a shield to protect the operator's hands from said ironing surface, and means operated by the pedal for moving the shield across the hot ironing surface when the jaws open and for moving the shield away when the jaws close.

7. An ironing press comprising in combination, cooperating ironing jaws one of which has a polished heated working face, means for opening and closing the press jaws, said jaws constructed rectangular in shape and having a wide open movement at the longitudinal axis thereof, a shield mounted on one of the jaws extending along the longitudinal edge thereof, and actuating mechanism connected with the shield and with the press opening and closing means by which the shield is moved across the press working face to protect the operator's hands and by which the shield is moved away to expose the press working face to the work.

8. An ironing press comprising in combination, cooperating ironing jaws one of which has a polished heated working face, means for opening and closing the press jaws, said jaws constructed rectangular in shape and having a wide open movement at the longitudinal axis thereof, a shield mounted on one of the jaws and extending along the longitudinal edge thereof from end to end, an actuating mechanism connected with the shield and with the press opening and closing means by which the shield is moved across the press working face to protect the operator's hands, a roller which acts to pull the shield back away from the heated ironing face, and means to drive the roller.

9. An ironing press comprising in combination, cooperating ironing jaws one of which is made with a polished heated ironing surface, a roller carried adjacent the ironing surface, a curtain carried upon the roller, and a single operating mechanism adapted to open and close the press and operate the said curtain.

10. An ironing press comprising in combination, cooperating ironing jaws one of which is made with a polished heated ironing surface, a roller carried adjacent the ironing surface, a curtain carried upon the roller, a pull link attached to each end of

the curtain extending alongside each end of the jaw and movable back and forth to operate the curtain, and a pedal connected with one of the jaws to open and close the press and connected with the pull link to operate the curtain.

11. An ironing press comprising in combination, cooperating ironing jaws one of which is provided with a hot polished ironing surface which acts on the work to be pressed, a roll up guard carried on the jaw having the ironing surface, operating means to open and close the press, and a linkage having connection with the guard and operating means by which the guard is drawn over the ironing surface as the press opens and is drawn away therefrom as the press closes.

12. An ironing press comprising in combination, cooperating ironing jaws one of which is provided with a hot polished ironing surface which acts on the work to be pressed, a roll up guard carried on the jaw having the ironing surface, guide brackets in which the guard travels, a swing linkage attached to the guard, means for operating the swing linkage as the press opens and closes, and mechanism for opening and closing the press and simultaneously operating the swing linkage.

13. An ironing press comprising in combination, cooperating ironing jaws one of which is provided with a hot polished ironing surface which acts on the work to be pressed, a roll up guard carried on the jaw having the ironing surface, guide brackets in which the guard operates, a press lever carrying one of the jaws and adapted to open and close the press, and an actuating device carried by the press lever and connected with the guard.

14. An ironing press comprising in combination, cooperating ironing jaws one of which is provided with a hot polished ironing surface which acts on the work to be pressed, a press lever carrying the polished ironing jaw and adapted to raise and lower it, a roll up guard curtain mounted on the press to protect operator's hands from the hot surface, a frame, actuating mechanism pivotally carried on the frame and connecting with the curtain, and means operated by the press lever to operate the mechanism.

15. An ironing press comprising in combination, cooperating ironing jaws one of which is provided with a hot exposed working surface, a press lever carrying one of the jaws and adapted to open the press thus exposing the hot working surface to the operator, a guard movably carried on the press and traveling back and forth across the hot working surface, a swing link pivoted on the press, a draw link connecting the swing link to the guard, and means actuated by the press lever to oscillate the swing link.

16. An ironing press comprising in combination, cooperating ironing jaws one of which is provided with a hot exposed working surface, a press lever carrying one of the jaws and adapted to open the press thus exposing the hot working surface to the operator, a roller curtain journaled on the press, a pull link attached to the curtain to

draw it across the hot surface, operator actuated means for opening and closing the press and simultaneously drawing on the pull link, and means related with the roller curtain to wind up said curtain as the press closes. 10

In testimony whereof I affix my signature.
ALBERT B. CLISSON.
